UNITED STATES PATENT OFFICE

163,607

TEXTILE FABRIC OR SIMILAR FLAT
SURFACE MATERIAL

Melvin L. Hucke, Dayton, Ohio, assignor to The
Dayton Rubber Company, a corporation of
Ohio

Application July 28, 1950, Serial No. 11,462

Term of patent 14 years

(Cl. D92—1)

To all whom it may concern:

Be it known that I, Melvin L. Hucke, a citizen of the United States, residing at Dayton, State of Ohio, have invented a new, original, and ornamental Design for a Textile Fabric or Similar Flat Surface Material, as shown in the accompanying drawing, of which the following is a specification.

The figure is a face view of a textile fabric or similar flat surface material showing my new design. Substantially a design unit is contained between the lines A—A' and B—B'. Said unit is composed of two halves identical except for the human figures crossed by said lines, which figures are repeated in alternate halves as indicated. Said halves of the design unit are contiguous at the line C—C. The design unit is repeated over the fabric vertically and horizontally on the drawing.

I claim:

The ornamental design for a textile fabric or similar flat surface material, as shown and described.

MELVIN L. HUCKE.
